(57) **CLAIM**

The ornamental design for a soft top for a sport utility vehicle, as shown and described.

DESCRIPTION

FIG. 1 is a perspective view of a soft top for a sport utility vehicle showing our new design.

FIG. 2 is a right side elevational view thereof, the left side elevational view being identical thereto.

FIG. 3 is a front elevational view thereof.

FIG. 4 is a rear elevational view thereof.

FIG. 5 is a top plan view thereof.

FIG. 6 is a bottom plan view thereof.

FIG. 7 is a perspective view of a soft top for a sport utility vehicle showing our new design.

FIG. 8 is a right side elevational view thereof, the left side elevational view being identical thereto.

FIG. 9 is a front elevational view thereof.

FIG. 10 is a rear elevational view thereof.

FIG. 11 is a top plan view thereof; and,

FIG. 12 is a bottom plan view thereof.

The broken lines in the drawings are for illustrative purposes only and form no part of the claimed design.
